INDICATING SYSTEM

Walter P. Venzke, Berlin, Germany, assignor to
 General Electric Company, a corporation of
 New York

Application August 17, 1934, Serial No. 740,319
 In Germany September 7, 1933

8 Claims. (Cl. 177—311)

My invention relates to indicating systems and concerns particularly arrangements for use in electric control stations to indicate the positions of switches or other movable parts in an electrical distribution system.

It is an object of my invention to provide an arrangement for displaying at any time a symbolic picture of the varying conditions of operation as well as the positions of switches in distribution networks.

It is a further object of my invention to provide such an arrangement which may be readily constructed at relatively little cost and in which the consumption of current and the production of waste heat will be reduced to a minimum.

Still another object is the provision of an indicating system in which the indications may be clearly and easily read.

In accordance with my invention in its preferred form, vibrating reed indicating elements are utilized for producing the position indications. The individual indicating elements may be used in conjunction with lines marked on a panel in the form of a diagram representing the conductors or the power lines in a distribution network. The vibrating reed elements may be so arranged that targets carried by the vibrating reeds move either at right angles to or along lines representing the electrical network for the purpose of producing the illusion of line segments intersecting the lines on the diagram to represent the connection of feeders to main buses or closing gaps in the lines of the diagram to represent the closing of switches in various portions of a power line or bus.

If desired, the lines of the diagram may also be produced wholly or in part by the targets of a number of adjacent vibrating reed elements for the purpose either of producing the illusion of a broadened line to represent a live section of a network or for the purpose of changing a broken line representing a dead section into a series of connected line segments to represent a live section of the network. This modification is claimed specifically in my copending divisional application Serial No. 137,070 filed Apr. 15, 1937.

The direction of flow of a flowing medium or the direction of power transfer in an electric system may also be represented symbolically by using the targets of a series of adjacent vibrating reed elements to represent a pipe line or electric power line and causing the vibrating reed elements to be energized in succession to produce the illusion of flow by the successive vibration of the targets along the line of targets in a direc-

tion corresponding to the direction of flow or power transfer.

The features of my invention which I believe to be novel and patentable will be pointed out in the claims appended hereto. A better understanding of my invention, itself, however, may be obtained by referring to the following description taken in connection with the accompanying drawings in which Fig. 1 represents schematically in a side view one of the vibrating reed elements and shows in cross section a fragment of the panel or indicating board on which the vibrating reed element is mounted. Figs. 2 to 9, inclusive, illustrate fragments of indicating panels constructed in accordance with various embodiments of my invention. Figs. 10 and 11 are circuit diagrams of arrangements for producing directional indications.

Referring now more in detail to the drawings in which like reference characters designate like parts throughout, in Fig. 1, the vibrating reed element is represented as consisting of an exciting winding 11 energized through a control circuit connected at the terminals 12. A vibrating reed 13 is set in motion by the energization of exciting winding 11 and a target 14 is carried on the end of the reed 13 to permit easy detection of the vibration of the reed 13. The vibrating reed element may be similar to such elements of a well known type used in vibrating reed frequency meters and, therefore, need not be described in detail.

I have found it satisfactory to mount the vibrating reed elements on the back of a panel, such as the panel 15, with each vibrating reed 13 projecting through an opening 16 in the panel so that the target 14 is positioned in front of the face of the panel 15. However, it will be understood that I am not limited to this precise construction and might, if desired, also arrange the target 14 to vibrate flush with the surface of panel 15 or in a recess. In the arrangement illustrated with the target 14 positioned in front of the panel 15, a channel 17 is provided preferably having a transparent front plate 18 to protect the vibrating elements and composed of any suitable material such as glass, synthetic resin, or the like.

To simulate the conductors of an electrical network or the pairs or groups of conductors forming an electric transmission line, a strip or line 19 may be painted on, pasted to, or otherwise affixed to the transparent front plate 18. In the arrangement illustrated in Figs. 1, 2, and 3, the strip or line 19 is continuous and the targets 14 are positioned behind the strip 19 so as to be

concealed when in their positions of rest. In Fig. 2 strip 19 represents a section of a distribution network with all lateral feeders disconnected, and the targets 14 being at rest are not visible behind the strip 19. Fig. 3 represents the condition where switches have been closed at two points represented by the points 14a and 14b, causing the vibrating reed elements to be energized and making the targets 14a and 14b of the two elements visible as lines intersecting the line 19 to simulate the connection of feeders at the two points. It will be understood that, owing to the high frequency of vibration of the targets 14a and 14b, elongated or extended images of them are produced and they appear to the eye as continuous lines or line segments as in the case of vibrating reed frequency meter elements.

Suitable control circuits are, of course, to be provided for simultaneously energizing reed windings 11 and operating the switches simulated or for energizing the reed windings in response to operation of the switches. Such circuits, however, are not part of my invention and need not, therefore, be described in detail. For example, in Fig. 1, if the vibrating reed element is intended to simulate a circuit breaker 1 adapted to connect a feeder circuit 2 to a bus 3, the circuit breaker 1 may be provided with an auxiliary set of contacts 4 serving to close a circuit from an auxiliary alternating current source 5 through the reed actuating winding 11 when the circuit breaker 1 assumes its closed position, thereby setting the reed 13 in vibration.

The vibrating reed element illustrated in Fig. 1 may be so arranged that the target 14 vibrates either transversely to the line 19 or in the same direction. If the direction of vibration is the same as the direction of the line 19, gaps may be left in the line 19 at 20 and 21 to simulate switches at these two points arranged to break an electrical network into several sections represented by the several segments of the broken line 19 as shown in Fig. 5. When the switches are closed, the corresponding vibrating reed elements are energized and the vibration of the targets 14a and 14b produces the illusion of line segments closing the gaps 20 and 21 and causing the line 19 to appear continuous, as in Fig. 2, to represent continuity of the power line represented by the diagram. The strips 19 and targets 14 may be given special colors, or coated with luminous paint to make the diagram especially clear.

If desired, distribution networks having switches both for isolating sections of the network and for connecting feeders to each section may also be represented by a diagram similar to that shown in Fig. 6 in which transversely vibrating reed elements are placed at 22, 23, and 24 to represent switches connecting sections to lateral feeders, and longitudinally vibrating elements are placed at 25 and 26 to represent switches for breaking up a portion of the network into sections.

If desired, the lines of the diagram representing the network may be wholly made up of the targets of vibrating reed elements as illustrated in Figs. 4 and 9. For example, in the arrangement of Fig. 4, the vibrating elements may be arranged to vibrate transversely. Then the narrow line composed of targets at rest represents a dead portion of the network and a broad line produced by vibrating targets might represent a live portion of the network.

If the targets in the arrangement illustrated

in Fig. 9 are arranged to vibrate longitudinally, an illusion of a continuous line will be produced when the vibrating elements are energized and the broken line represented by targets at rest may represent a dead portion of a network. The continuous line represented by the vibrating targets may represent a live portion of the network.

My invention is not limited merely to indicating the positions of switches or other movable elements of an electrical network or to indicating whether sections of a network are alive or dead but may also be adapted to the production of other indications, for example, an indication of the direction in which power is flowing or being transferred in an electrical system. For example, if a power line simulating diagram is made up of a plurality of vibrating elements, as illustrated in Figs. 4 and 9, the vibrating elements may be arranged to be energized progressively from one end of the diagram to the other instead of simultaneously for the purpose of producing an illusion of flow. Obviously, the successive vibrations of the targets 14 along the line of targets would produce a very effective symbol of power flow.

Any suitable method may be employed for energizing the vibrating reed elements progressively. For example, as illustrated in Fig. 10, each of the elements may be connected through a control circuit to an inductance and the inductances may be given progressively increasing values in order to cause each element to have a different time lag of response, in this way causing the vibrations to take place progressively.

In the arrangement shown in Fig. 10, a plurality of vibrating reed elements 14a, 14b, 14c, and 14d have their actuating windings 11a, 11b, 11c, and 11d connected to an auxiliary source of alternating current 5 through the contacts of a set of relays 27a to 27d which, in turn, are controlled by a power directional relay 28 responsive to the direction of power transfer in a three-phase transmission line 29. The windings of the relays 27a to 27d are connected to a source of auxiliary current 30 through one or the other of alternative pairs of contacts 31 and 32 of the power direction relay 28 and through inductances 33a to 33d, varying successively in value.

Preferably, relays 34a to 34d, adapted to permit current to flow only a predetermined length of time and then restore the circuit again after another predetermined duration of circuit interruption are also connected in series with the windings 27a to 27d. The relays 34a to 34d, for example, may be of the bimetallic thermostatic strip type which become heated after current has flowed a predetermined length of time, bending away from the stationary contacts to open the circuit and then being cooled to close the circuit again after another predetermined length of time.

When the direction of power transfer is such that the power directional relay 28 closes its contacts 32 the relay 27a will be connected directly through a source 30 to thermostatic relay 34a and vibrating reed element 14a will be set in vibration, continuing to vibrate until the relay 34a opens. A circuit will also be closed through winding 27b, the upper half of inductance 33b, and thermostatic relay 34b to the source 30. Owing to the inductance in the circuit, the closing of relay 27b will be later than the closing of relay 27a, and vibrating reed element 14b will start vibrating slightly later than element 14a but will vibrate for the same period of time as the ele- 75

ment 14a. In a similar manner, relay 27c, connected through the inductance 33c will be further delayed, and relay 27d, connected through inductance 33d of greater value, will be still further delayed. Consequently, the vibrating reed elements 14a to 14d will be set in vibration progressively and successive waves of vibration will appear to travel down the row of vibrating reed elements to indicate the direction of power transfer. If the direction of power transfer reverses so as to close the contacts 31 instead of the contacts 32, the relay 27d will, of course, be directly connected to the source 30 without any inductance in the circuit and the relays 27c, 27b, and 27a will be connected through successively increasing amounts of inductance to reverse the order in which the vibrating reed elements 14a to 14d are actuated.

The vibrating reed elements may also be progressively actuated in a direction dependent upon the direction of power transfer by means of a rotary switch 35 (Fig. 11) driven by a power directional relay 36 of the inductance disc motor type, which is well known and need not be described in detail. The moving blade 37 of the rotary switch 35 progressively engages the stationary contacts 38a, 38b, 38c, and 38d to close circuits progressively through the reed-actuating windings 11a to 11d. Upon reversal in direction of power transfer the direction of rotation of the motor 36 and the switch blade 37 reverses. While I have described specific arrangements for progressively actuating vibrating reed elements, it will be understood that I am not limited to the exact arrangements which I have disclosed.

Although my invention is particularly well adapted to use with electrical networks, it will be understood, of course, that it is not limited thereto but may also be used for the symbolic indication of conditions of operation in other systems having a flowing medium. For example, in water or gas distributing systems, the opening or closing of valves in a pipe line or in laterals may be represented by vibrating targets as illustrated in Figs. 5 or 3, respectively. Similarly, the direction of flow of any other medium, as well as the direction of power transfer of electricity, may be represented by causing the vibrating reeds to be energized progressively as previously explained.

If desired, transient conditions in electrical networks may be represented by flicker indications similar to the flicker lights used in luminous line diagrams by energizing the vibrating reed elements with intermittent alternating current or by using alternating current modulated with another frequency. For example, a relay actuated by transient currents may be utilized to connect vibrating reed elements to a source of intermittent alternating current upon the occurrence of a transient.

Obviously, high precision is not required in the manufacture of the reed elements, since the vibrating reeds may be broadly tuned to any frequency near the frequency of the current source, for example, from 59.5 to 60.5 cycles for 60 cycle systems.

My invention may also be used in conjunction with direct control currents when it is desired to produce indications of direction or indications of which of two alternative switches is closed. For example, in the arrangement of Figs. 7 and 8, the targets 14 may be deflected in one direction by direct currents of a given polarity to represent the closing of switches connecting a line to one circuit and may be deflected in the opposite

direction to represent the closing of switches connecting a line to a different alternative circuit or to represent the reversal of position of double-throw switches. If desired, the arrangement of Fig. 8 may also be utilized to represent the continuity or interruption of an electrical circuit by causing the targets 14 to deflect out of line when the circuit is interrupted and to drop back in alignment with the line 19 when the circuit is continuous.

I have herein shown and particularly described certain embodiments of my invention and certain methods of operation embraced therein for the purpose of explaining its principle and showing its application but it will be obvious to those skilled in the art that many modifications and variations are possible and I aim, therefore, to cover all such modifications and variations as fall within the scope of my invention which is defined in the appended claims.

What I claim as new and desire to secure by Letters Patent of the United States is:

1. An indicating arrangement comprising in combination, an indicating plate having a line thereon representing a line of flow with a gap in said line representing means for interrupting flow, and a vibrating reed indicator having a target located in said gap in its position of rest and having means for vibrating said target through the distance of said gap, thus apparently closing said gap when said target is set in vibration to indicate that the means for interrupting flow has been set to the position permitting flow.

2. An arrangement for indicating a connection between two members comprising in combination, a panel having a line thereon with a gap in said line to represent a lack of connection between said two members, and a vibrating reed indicating element having a target in alignment with said line in its position of rest and having means for setting said target in vibration in the direction of said line with an amplitude corresponding substantially to the length of the gap in said line to produce the illusion of a line segment completing said first mentioned line for the purpose of indicating a connection between the two members.

3. An arrangement for indicating the position of a switch adapted to connect two conductors comprising in combination, a panel having a line thereon representing one of the electrical conductors, and a vibrating reed indicating element having a target in alignment with said line in its position of rest and having means for vibrating said target in a plane parallel to said panel through a path, joining the projection of said line on said plane to produce by persistence of vision an illusion of a line segment connecting with said first mentioned line to represent by the apparent connection of said line and said line segment the closing of a switch joining the second conductor to said first mentioned conductor.

4. A switch position indicator comprising in combination, a panel having a line marked thereon to represent an electrical conductor, and a vibrating reed indicating element having a target concealed under a portion of said line in its position of rest and having means for vibrating said target transversely to said line to produce the illusion of a line segment intersecting said line to represent the closing of a switch connecting a second conductor to said first mentioned conductor at a point represented by the position of said vibrating reed.

5. An indicating arrangement for an electrical network comprising a channel enclosing a line representing a portion of the electrical network and a vibrating reed element having a target on said line in its position of rest and means for setting said target in vibration when said portion of the network is energized, producing the illusion of a visible line segment touching said line to represent a condition of energization of said network at a point represented by said vibrating reed element.

6. In a line diagram indicating system for an electrical network, a supporting panel, a channel mounted on the front of said panel having a center line representing a portion of the electrical network, a vibrating reed element mounted on the back of said panel, having a reed carrying a target and reed-vibrating means energized with said portion of the electrical network, said panel having an aperture therein through which said reed projects to the front, said target in its position of rest being in alignment with the center line of said channel and being vibrated during energization of the vibrating means to produce the illusion of a visible line segment representing 25 a condition of energization at a point in the elec-

trical network represented by said vibrating reed element.

7. A line diagram indicating arrangement comprising in combination, a supporting panel with a line marked thereon, a vibrating reed element thereon having a target and means for vibrating said target in response to a condition, the existence of which is to be indicated, the path of vibration of said target meeting said line, whereby vibration of said target produces the illusion of 10 a line segment forming with said panel line a figure representing the condition to be indicated.

8. A switch position indicator comprising in combination, a panel having a line marked thereon representing an electrical conductor with a 15 gap in said line representing a switch interposed in said conductor, and a vibrating reed indicating element having a target forming a point in said gap in its position of rest and having means for vibrating said target in a plane including 20 said line and substantially parallel thereto along said gap to produce the illusion of closing the gap in said line to represent the closing of said switch.

WALTER P. VENZKE. 25
